L. JOSEPH

COMBINED MIRROR, SOAP RECEPTACLE, AND BRUSH HOLDER

Filed Oct. 20, 1925

FIG. 3.

INVENTOR
Lev Joseph
BY
Fritz Ziegler Jr.
ATTORNEY

UNITED STATES PATENT OFFICE.

LEW JOSEPH, OF NEW YORK, N. Y.

DESIGN FOR A COMBINED MIRROR, SOAP RECEPTACLE, AND BRUSH HOLDER.

Application filed October 20, 1925. Serial No. 15,200. Term of patent 3½ years.

To all whom it may concern:

Be it known that I, LEW JOSEPH, a citizen of the United States, residing in the borough of Manhattan, city, county, and State of New York, have invented a new, original, and ornamental Design for a Combined Mirror, Soap Receptacle, and Brush Holder, of which the following is a specification, reference being had to the accompanying drawing, forming part hereof.

Fig. 1 is a front elevation, Fig. 2 is a side elevation and Fig. 3 is a top plan view of my new combined mirror, soap receptacle and brush holder.

I claim:

The ornamental design for a combined mirror, soap receptacle, and brush holder, as shown in the accompanying drawing.

LEW JOSEPH.
